UNITED STATES PATENT OFFICE.

EDWIN OLSEN, OF MILWAUKEE, WISCONSIN, ASSIGNOR, BY MESNE ASSIGNMENTS, TO
MILWAUKEE ICE MACHINE COMPANY, OF MILWAUKEE, WISCONSIN, A CORPOR-
ATION.

DESIGN FOR A CONDENSER AND MOTOR AND COMPRESSOR BASE.

6,302.

Specification for Design.

Patented Sept. 14, 1920.

Application filed December 1, 1917. Serial No. 204,987. Term of patent 14 years.

To all whom it may concern:

Be it known that I, EDWIN OLSEN, a citizen of the United States, residing at Milwaukee, in the county of Milwaukee and State of Wisconsin, have invented a new, original, and ornamental Design for a Condenser and Motor and Compressor Base, of which the following is a description, reference being had to the accompanying drawing, forming part thereof.

The figure is a perspective view of the condenser and motor and compressor base showing my new design.

I claim:

The ornamental design for a condenser and motor and compressor base, as shown.

EDWIN OLSEN.
